UNITED STATES PATENT OFFICE.

IRA D. CADY, OF MINNEAPOLIS, MINNESOTA.

HOLDBACK-HOOK.

No. 927,220.

Specification of Letters Patent.

Patented July 6, 1909.

Application filed February 2, 1909. Serial No. 475,597.

To all whom it may concern:

Be it known that I, IRA D. CADY, of Minneapolis, Hennepin county, Minnesota, have invented certain new and useful Improvements in Holdback-Hooks, of which the following is a specification.

My invention relates to shaft hold-back hooks, to which the breeching strap is attached and the object of my invention is to 10 provide a hook device, which is capable of separation from the shaft and is adapted to be easily and quickly attached thereto in harnessing a horse.

A further object is to provide a hold-back 15 that is capable of ready separation from the shaft, but cannot possibly become accidentally detached therefrom while the device is in use.

Other objects of the invention will appear 20 from the following detailed description.

The invention consists generally in a housing having means for securing it to a shaft, and a loop adapted to be attached to a breeching strap and having a hook member 25 arranged to enter said housing and be temporarily locked therein.

Further, the invention consists in a peculiar 30 construction of hook, which will resist backward pull thereon, but be readily separated from the housing, when a forward pull is exerted on the hook.

Further, the invention consists in various 35 constructions and combinations, all as hereinafter described and particularly pointed out in the claim.

In the accompanying drawings, forming 40 part of this specification, Figure 1 is a side view of a portion of a shaft, with my improved hold-back hook applied thereto, Fig. 2 is a bottom view, illustrating the manner of pulling the hook out of its housing or 45 socket, when a forward pull is applied thereto, Fig. 3 is a detail, sectional view, illustrating the spring device within the housing for holding the hook in position to resist a backward pull of the breeching strap.

In the drawing, 2 represents a shaft, 3 a breeching strap and 4 a plate having means 50 for securing it, preferably to the under side of a shaft. Within this plate is a chamber 5, inclosing a U-shaped spring 6. A slot 7 is formed in one wall of the housing and a loop 8 is attached to the breeching strap and

has a curved part 9, that is adapted to slip through the slot 7 and is provided with a 55 rounding surface 10 to contact with the spring 6. The part 9 is shaped somewhat in the form of a shoe, the toe thereof bearing on the spring 6 and the heel having a square surface 11, which contacts with the rear edge 60 of the slot 7 when a backward pull is exerted on the loop portion 8 through the breeching strap 3. A compression spring 12 is provided between the ends of the spring 6, to resist the pressure on the spring and contacting with the toe of the part 9, and to hold its rear edge 11 in engagement with the edge of the slot 7. As long therefore, as pressure is applied to this toe, it will be impossible for any strain on the breeching strap to withdraw the device from its socket, but as soon as a forward pull is exerted on the loop 8, the toe of the part 9 will be forced inwardly and the said part rotated slightly in its socket until the heel 11 is pulled away from contact 75 with the rear edge of the slot 7. Thus, it will be very easy to unhitch a horse as soon as the traces or tugs are released. In fact, in practice, it will not be necessary to apply the hands to the hold-back hooks, but after 80 unhooking the tugs from the swingletree, the horse can walk out of the shaft and the hold-back hooks swinging forward, will automatically be disengaged from their connections with the shaft.

I prefer to arrange the loop 8 with respect 85 to the part 9, as indicated in Fig. 1, so that the pull of the breeching strap will be applied more evenly to the loops.

This device, it will be noted, is extremely 90 simple in construction, has no small, intricate parts to get out of order and can be easily applied to any make of shaft.

I claim as my invention:

The combination, with a shaft, of a housing 95 mounted thereon, a U-shaped spring provided within said housing, a coil spring arranged between the ends of said U-shaped spring, said housing having a slot in its wall, a loop adapted to be connected to the breeching strap and having a shoe fitting within the slot in said wall and provided with a curved surface to contact with said U-shaped spring, said shoe also having a square edge 100 adapted to contact with the wall at the back 105 end of said slot, said shoe edge resisting

backward pull of said breeching strap on said shoe, and said U-shaped spring being compressed by a forward pull on said shoe and allowing said shoe to be drawn forward 5 out of said slot and against the tension of said compressed spring substantially as described.

In witness whereof, I have hereunto set my hand this 19th day of January 1909.

IRA D. CADY.
